DESIGN FOR AN AIR CONDITIONING CABINET OR SIMILAR ARTICLE

Ralph E. Kruck, Springfield, Mass., assignor to
Westinghouse Electric & Manufacturing Com-
pany, a corporation of Pennsylvania

Application September 19, 1933. Serial No. 49,297

Term of patent 7 years

To all whom it may concern:

Be it known that I, RALPH E. KRUCK, a citizen
of the United States residing at Springfield, in
the county of Hampden and State of Massachu-
setts, have invented a new, original, and orna-
mental Design for an Air Conditioning Cabinet
or Similar Article, of which the following is a
specification, reference being had to the ac-
companying drawing constituting a part hereof.

The single figure is a perspective view of an

air conditioning cabinet showing my new de-
sign.

I claim:

The ornamental design for an air condition-
ing cabinet or similar article, substantially as
shown.

In witness whereof, I have hereunto sub-
scribed my name this fifth day of September,
1933.

RALPH E. KRUCK.
